UNITED STATES PATENT OFFICE.

HARRY JOSEPH FISHER, OF PHILADELPHIA, AND JAMES MIRREY, OF EAST BOLDON, ENGLAND, ASSIGNORS TO A. REYROLLE & COMPANY LIMITED, OF HEBBURN-ON-TYNE, DURHAM, ENGLAND, A BRITISH COMPANY.

INTERLOCKED FASTENING DEVICE PARTICULARLY APPLICABLE TO ELECTRICAL APPARATUS.

Application filed April 14, 1924. Serial No. 706,587.

To all whom it may concern:

Be it known that we, HARRY JOSEPH FISHER and JAMES MIRREY, subjects of the King of England, and residing, respectively, at Philadelphia, in the county of Durham, England, and East Boldon, in the county of Durham, England, have invented certain new and useful Improvements in Interlocked Fastening Devices Particularly Applicable to Electrical Apparatus, of which the following is a specification.

This invention relates to a fastening device for securing two members together of the type in which the device is interlocked with some other mechanism in such a manner that the two members cannot be caused to engage with one another or to disengage except when the other mechanism is in some definite position.

20 The invention is more particularly applicable to electrical apparatus, and is primarily designed with the object of providing an electrical plug and socket connection, where in the plug can only be inserted in the socket before a controlling switch or other mechanism has been operated and cannot be withdrawn from the socket until after the switch or other mechanism has been returned to its initial position.

30 The fastening device according to the present invention comprises a bolt or rod pivoted to one of the two members to be secured together, and a drum or sleeve movable longitudinally thereon. A part of the drum or a projection thereon is so shaped as to lie in or out of the path of an interlocking rod according to the position of the drum on the bolt. The drum is caused to move along the bolt by means of a rotatable head or the like, which also engages with the second of the two members in such a manner as to clamp these members together in the engaging position.

45 The rotatable head may have two flanges adapted to engage respectively with the two sides of a slotted lug on the second member so as to assist the engagement or separation of the two members. The drum is held against rotation relative to the bolt and conveniently its projection lies in the path of the interlocking rod except when the two members are clamped together. The rotatable head is preferably formed with a

screw-thread engaging in a corresponding thread on the drum, a spring being provided 55 between the drum and a collar on the bolt in such a manner as to tend to move the drum into a position in which its projection lies in the path of the interlocking rod.

The invention may be carried into practice 60 in various ways and may be applied to a variety of purposes, but the accompanying drawings illustrate by way of example a preferred arrangement as applied to an electrical plug and socket connection, more particularly intended for use in mines and other places where it is of great importance to prevent the occurrence of a spark by ensuring that the controlling switch is returned to the off-position before the plug is inserted in or withdrawn from the socket. In 65 these drawings,

Figure 1 shows the interlocking bolt in horizontal section in the closed position,

Figure 2 is a plan of the bolt in the open 70 position, and

Figure 3 is a side elevation of the bolt.

In these drawings the socket A has pivoted to it two or more bolts, one of which B is employed for interlocking purposes according to the invention. The remaining bolts (not shown in the drawings) carry winged nuts which engage with slotted lugs on the plug C, so as to clamp the plug in 80 position in the socket A. These nuts each carry two flanges which engage with one side or the other of the corresponding lug and thus assist in withdrawing the plug from the socket or in inserting it therein.

The bolt B used for the interlock is pivoted at B' to lugs A' on the socket and is surrounded by a drum D which is free to move longitudinally on the bolt but is keyed or slotted as at D' to prevent it from rotating relative to the bolt B. A winged head E, having two flanges E' E² which engage respectively with one side or the other of a slotted lug C' on the plug C, is provided for this bolt B, and is furnished with a screwthread engaging in a corresponding 85 thread in the drum D. A spring F is provided between the drum D and a collar B² fixed to the bolt B in such a manner as to tend to move the drum towards the pivot B' of the bolt. The bolt has a stop B³ at its outer end, which prevents the head E from 90

being detached completely from the drum D. The end B³ of the bolt is arranged never to project beyond the head E so that the operator's hand is protected from damage.

The drum D has a lateral projection D² which is moved into and out of the path of an interlocking rod G as the head E is rotated. Thus when the plug C is clamped 10 into the socket A, as shown in Figure 1, this projection D² lies out of the path of the interlocking rod G, which is therefore free to move. When, however, the head E is unscrewed to withdraw the plug C from the 15 socket A, the drum D travels along the bolt B and brings the projection D² into the path of this rod G.

The interlocking rod G may be connected to any desired mechanism such for example 20 as a switch controlling the electrical circuit containing the plug and socket. Thus when the plug is clamped in the socket and the projection D² is out of the path of the interlocking rod G, the switch may be operated. 25 When the switch is turned into the "on" position, this rod G moves into the path of the projection D² and prevents the head E from being unscrewed far enough to withdraw the plug. In Figure 3 the rod G is shown in this 30 position, whilst the "off" position of the end of the rod is indicated in chain line at G'.

When the plug C is clamped in the socket A, the outer flange E' of the head E is held tightly against the lug C' on the plug by 35 means of the spring F, this spring being made strong enough to prevent the plug from being withdrawn except by unscrewing the head E. When it is desired to withdraw the plug from the socket, the switch must be 40 turned "off" to remove the interlocking rod G from the path of the projection D² on the drum D. The head E is then unscrewed and the drum D moves down along the bolt B under the action of the spring F, the outer 45 flange E' of the head E still remaining in contact with the slotted lug C'. After the drum D has reached the end of its travel and its projection D² lies in the path of the interlocking rod G, the head E begins to move as 50 it is rotated until its inner flange E² comes into contact with the other side of the slotted lug C'. The winged nuts on the other retaining bolts are also unscrewed until their inner flanges engage with the lugs, and further 55 rotation of the head and the nuts causes the plug to begin to move out of the socket. The bolts are then swung out about their pivots until the head and the nuts cease to engage with the slotted lugs and the plug 60 can be completely removed. This position is shown in Figure 2. Since the projection D² on the drum D now lies in the path of the interlocking rod G, it is impossible to operate the switch while the plug is out of the 65 socket. No current can therefore be flowing

through the circuit while the plug is being withdrawn from or inserted into the socket, and it is therefore impossible for a spark to occur. It is also impossible for the terminals of the socket to be exposed when the switch 70 is "on" and thus for anyone to receive a shock by touching the live socket terminals.

To clamp the plug into position in the socket, it is first of all inserted therein and the bolts are swung in until the nuts and the 75 head are in engagement with the slotted lugs. Tightening up these members then forces the plug right home into the socket (this action being assisted by the spring F) and clamps it into position. Further rotation of the head E moves the drum D along the bolt B until its projection D² is again 80 out of the path of the interlocking rod G. The switch can now be operated, and the 85 plug cannot again be withdrawn until the switch is in the "off" position.

It will be understood that the construction described is given only by way of example and the details of construction may be varied without departing from the scope of the invention. Thus for example the head may make a screw-threaded engagement with the bolt as well as with the drum, the necessary motion of the drum being caused owing to a 90 difference between the pitches of the two threads. Modifications may also be made to suit the requirements of any particular purpose to which the fastening device according 95 to the invention is applied.

What we claim as our invention and desire to secure by Letters Patent is:—

1. In a fastening device adapted to secure two members together and to be interlocked with some other mechanism, the combination 105 with the two members, of a bolt pivoted to one of the members, a rotatable head adapted to engage with the second member in such a manner as to clamp the two members together in the engaging position, a drum so connected to the head and the bolt as to move longitudinally along the bolt when the head is rotated, and an interlocking rod operated by the mechanism with which the fastening device is to be interlocked, the arrangement 110 being such that a part of the drum lies in or out of the path of the interlocking rod according to the position of the drum on the bolt.

2. In a fastening device, the combination 115 of the two members which are to be secured together by the device, a bolt pivoted to one of the members, a slotted lug on the second member, a rotatable head having two flanges adapted to engage respectively with the two 120 sides of the slotted lug so as to assist in the engagement or separation of the two members when the head is rotated a drum movable longitudinally on the bolt but held against rotation relative thereto, means 125 whereby the drum is caused to travel along 130

the bolt when the head is rotated, an interlocking rod operated by some other mechanism with which the fastening device is to be interlocked, and a projection on the drum 5 which lies in the path of the interlocking rod except when the two members are clamped together.

3. In a fastening device adapted to secure two members together and to be interlocked 10 with some other mechanism, the combination with the two members, of a bolt pivoted to one of the members, a rotatable head adapted to engage with the second member in such a manner as to clamp the two members 15 together in the engaging position, a drum movable longitudinally on the bolt but held against rotation relative thereto, the drum being provided with a screwthread engaging with a corresponding thread on 20 the head whereby the drum is caused to travel along the bolt when the head is rotated, an interlocking rod operated by the mechanism with which the fastening device is to be interlocked, and a projection on the 25 drum which lies in the path of the interlocking rod except when the two members are clamped together.

4. In a fastening device, the combination 30 of the two members which are to be secured together by the device, a bolt pivoted to one of the members, a slotted lug on the second member, a rotatable head having two flanges adapted to engage respectively with the two sides of the slotted lug so as to assist 35 in the engagement or separation of the two members when the head is rotated, a drum movable longitudinally on the bolt but held against rotation relative thereto, the drum being provided with a screwthread 40 engaging with a corresponding thread on the head whereby the drum is caused to travel along the bolt when the head is rotated, and an interlocking rod operated by some other mechanism with which the fastening device 45 is to be interlocked, the arrangement being such that a part of the drum lies in or out of the path of the interlocking rod according to the position of the drum on the bolt.

5. In a fastening device, the combination

of the two members which are to be secured together by the device, a bolt pivoted to one of the members, a slotted lug on the second member, a rotatable head having two flanges adapted to engage respectively with the two sides of the slotted lug so as to assist in the engagement or separation of the two members when the head is rotated, a drum movable longitudinally on the bolt but held against rotation relative thereto, the drum being provided with a screwthread engaging with a corresponding thread on the head whereby the drum is caused to travel along the bolt when the head is rotated, an interlocking rod operated by some other mechanism with which the fastening device is to be interlocked, and a projection on the drum which lies in the path of the interlocking rod except when the two members are clamped together, and a spring which tends to move the drum into a position in which its projection lies in the path of the interlocking rod.

6. In a fastening device adapted to secure two members together and to be interlocked 75 with some other mechanism, the combination with the two members, of a bolt pivoted to one of the members, a rotatable head adapted to engage with the second member in such a manner as to clamp the two members together in the engaging position, a drum movable longitudinally on the bolt but held against rotation relative thereto, the drum being provided with a screwthread 80 engaging with a corresponding thread on the head whereby the drum is caused to travel along with the bolt when the head is rotated, an interlocking rod operated by the mechanism with which the fastening device is to be interlocked, a projection on the drum 85 its projection lies in the path of the interlocking rod according to the position of the drum on the bolt, and a spring which tends to move the drum into a position in which its projection lies in the path of the interlocking rod.

In testimony whereof we have signed our names to this specification.

HARRY JOSEPH FISHER.
JAMES MIRREY.
